Primary Examiner — Thomas Johannes*Assistant Examiner* — Samantha Q Lawrence(74) *Attorney, Agent, or Firm* — Wednesday G. Shipp(57) **CLAIM**

The ornamental design for a diaper, as shown and described.

DESCRIPTION

FIG. 1 is a perspective view of a diaper;

FIG. 2 is a bottom view thereof;

FIG. 3 is a top view thereof;

FIG. 4 is a right side view thereof;

FIG. 5 is a left side view thereof;

FIG. 6 is a front view thereof, and,

FIG. 7 is a rear side view thereof.

The broken lines shown in FIGS. 1-7 illustrate portions of the diaper that form no part of the claimed design.

The dash-dot line indicates a boundary line that forms no part of the claimed design.
